(57) **CLAIM**

We claim the ornamental design for a buffer, as shown and described.

DESCRIPTION

FIG. 1 is a rear perspective view of a buffer in accordance with an embodiment of the present invention.

FIG. 2 is a left side view of the buffer of FIG. 1.

FIG. 3 is a right side view of the buffer of FIG. 1.

FIG. 4 is a front view of the buffer of FIG. 1.

FIG. 5 is a rear view of the buffer of FIG. 1.

FIG. 6 is a top view of the buffer of FIG. 1.

FIG. 7 is a bottom view of the buffer of FIG. 1.

FIG. 8 is a rear perspective view of a buffer in accordance with another embodiment of the present invention.

FIG. 9 is a left side view of the buffer of FIG. 8.

FIG. 10 is a right side view of the buffer of FIG. 8.

FIG. 11 is a front view of the buffer of FIG. 8.

FIG. 12 is a rear view of the buffer of FIG. 8.

FIG. 13 is a top view of the buffer of FIG. 8.

FIG. 14 is a bottom view of the buffer of FIG. 8.

FIG. 15 is a rear perspective view of a buffer in accordance with yet another embodiment of the present invention.

FIG. 16 is a left side view of the buffer of FIG. 15.

FIG. 17 is a right side view of the buffer of FIG. 15.

FIG. 18 is a front view of the buffer of FIG. 15.

FIG. 19 is a rear view of the buffer of FIG. 15.

FIG. 20 is a top view of the buffer of FIG. 15; and,

(Continued)

FIG. 21 is a bottom view of the buffer of FIG. 15. The portions of the buffer shown in broken lines are included for the purpose of illustrating environment and form no part of the claimed design.
